(57) **CLAIM**

(**) Term: **14 Years**

The ornamental design for a tendon sheath dissection tip for a surgical instrument, as shown and described.

(21) Appl. No.: **29/361,243**

DESCRIPTION

(22) Filed: **May 7, 2010**

FIG. 1 is a top perspective view of a tendon sheath dissection tip for a surgical instrument, comprising a new design;

(51) **LOC (9) Cl.** **24-02**

FIG. 2 is a bottom perspective view shown in FIG. 1;

(52) **U.S. Cl.** **D24/146; D24/144**

FIG. 3 is a top view shown in FIG. 1;

(58) **Field of Classification Search** **D24/144,**

D24/146–147, 133, 108; 600/190, 203, 167,
600/171–172, 129; 606/108, 129, 159, 184–185,
606/190–191, 139, 1

FIG. 4 is a cross-section of a center cutting blade as seen in the direction of line 4—4 of FIG. 3;

See application file for complete search history.

FIG. 5 is a cross-section of the center cutting blade as seen in the direction of line 5—5 of FIG. 3;
